UNITED STATES PATENT OFFICE.

LEO ROSENMAN, OF NEWARK, NEW JERSEY, ASSIGNOR TO R. K. M. MFG. COMPANY, A CORPORATION OF NEW JERSEY.

FASTENER STRIP OR FLY FOR GARMENTS.

Application filed May 24, 1922. Serial No. 563,209.

This invention has reference, generally, to a novel means and method of mounting garment-fasteners, such as hooks and eyes to strips or flies to be used with garments; and, 5 the present invention has for its principal object to secure the fasteners to the strips or flies in such a manner, that the strip or fly, when viewed from the front thereof will not display thereon the line or lines of 10 stitching by means of which the garment-fasteners are secured in place.

The present invention has for its further object to provide a fly comprising a main or base-strip and a front or face-strip, the latter being secured to said main or base-strip in a flattened-out condition by means of a line of sewing or stitching, the said front or face strip being folded over upon said line of stitching, so that the latter is 20 hidden from view, and that no line or lines of stitching are exposed to view upon the front face of the completed fly, the line of stitching being also made in a manner that the fasteners can be easily and quickly, as 25 well as securely and positively, arranged in their operative relation to the finished fly.

Other objects of the present invention not at this time more particularly enumerated will be clearly understood from the following detailed description of the present invention.

With the various objects of the present invention in view, the said invention consists, primarily, in the novel arrangements 35 and combinations of the several devices and parts, and in the novel means and method of securing the fly-members or elements in their secured relation, so that the connecting line or lines of stitching will not be exposed to view upon the front face of the 40 finished fly, and also that the fasteners will be secured in place against movement and accidental displacement, all of which will be more fully described in the following 45 specification, and then finally embodied in the clauses of the claims, which are appended to and which form an essential part of the said specification.

The invention is clearly illustrated in the 50 accompanying drawings, in which:—

Figure 1 is a front face view of fragmentary portions of a pair of flies, one fly being provided with hooks and the other fly being provided with eyes, said flies being made 55 according to and embodying the principles

of the present invention, and being shown in their separably connected relation by means of the hooks and eyes, which are indicated in dotted outline.

Figure 2 is a front face view of the fragmentary portion of one of said flies shown in said Figure 1, in this instance, the one which is provided with garment-fasteners, in the form of eyes; and Figure 3 is a rear face view of the fly shown in said Figure 2. 60 65

Figure 4 is a cross-sectional representation of said fly, said section being taken on line 4—4 in said Figure 2; and Figure 5 is a similar sectional representation of the fly, said section being taken on line 5—5 in said 70 Figure 2.

Figure 6 is a rear face view of the fragmentary portion of the fly shown in said Figure 2, before the front or face strip of the fly is folded over upon the main or base-strip, 75 said view illustrating the line of stitching for securing the said front or face-strip to said main or base-strip, and also showing one method of securing the garment fasteners in place; and Figure 7 is a transverse 80 vertical section of the parts shown in said Figure 6, said section being taken on line 7—7 in said Figure 6.

Figure 8 is a transverse vertical sectional representation of a modified form of main or 85 base-strip and a front or face strip, showing a slightly different arrangement of the connected members, and still embodying the principles of the present invention; and Figure 9 is a similar sectional representation 90 of the members shown in said Figure 8, before the front or face-strip is folded over upon the main or base-strip, said view showing, also, the method of securing said front or face-strip to the main or base-strip. 95

Figure 10 is a view of a fragmentary portion of a fly, said view showing a portion of the front or face-strip ripped away from the main or base-strip, to illustrate still another modified arrangement of the various parts; 100 Figure 11 is a transverse vertical sectional representation of the said parts, said section being taken on line 11—11 in said Figure 10; and Figure 12 is a rear face view of the parts represented in said Figures 10 and 11, 105 said view showing a portion of the main or base-strip ripped away from the front or face-strip, and folded back, to illustrate more particularly the general arrangement and method of securing a garment-fastener 110

or fasteners between the folded portions of the said main or base-strip.

Similar characters of reference are employed in all of the said above described views, to indicate corresponding parts.

Referring now to Figures 1 to 7 inclusive, the reference-characters 1 and 2, in Figure 1, indicate what is known in the trade as flies, the same being of any desired fabric to be suitably secured to a garment in a manner to be presently more fully described. Employed with one of said flies, as 1, is an arrangement of hooks 3, and employed with the other of said flies, as 2, is an arrangement of eyes 4. In either case, the construction and arrangement of the members which constitute a fly, whether used with the hooks 3, or with the eyes 4, being the same, I will hereafter refer to and describe the construction merely of the fly indicated by the reference-character 2, and the eyes 4 employed in connection therewith.

As shown, the main fly consists, essentially, of a base strip 5, which is longitudinally folded, as at 6 and 7, so as to provide two folds 8 and 9, one fold of which, as 8, is usually of greater width than the fold 9, and of a front or face-strip 10, which is also longitudinally folded, as at 11 and 12, so as to provide two folds 13 and 14, one of said folds, as 13, being of greater width than the fold 14. Suitably disposed between the adjacent surface-portions of the said base-strip 5 and the front or face-strip 10, in a manner as shown more particularly in Figure 4 of the drawings, are suitably spaced garment-fasteners, as the eyes 4, the hook-receiving eye-portions 15 of which project slightly beyond the longitudinally folded edges 11 of the front or face-strip 10. Before the fold 13 is made, the front or face-strip 10 is left in a flattened out relation to the main base-strip 5, as shown in Figure 7 of the drawings, and the two members 5 and 10 then secured together by means of a row of stitching, as 16, in which is made at the desired intervals suitable jump-stitchings, as 17, see Figures 3 and 6, forming suitable retaining loops for the reception of the eye or hook-portions of the fasteners, and whereby the latter are securely maintained in their operative relation to the said main or base-strip 5 and the said front or face-strip 10 secured thereto by means of said stitching. The fold 13 is now turned over so as to lie upon the main portion of the strip 10, thereby entirely covering and hiding the stitching 16 from view, the main portions of the metal fasteners, except the slightest portions of the eyes or hooks, as the case may be, being also covered, so as to be hidden from view. The fold 14 heretofore-mentioned, and which is connected with the fold 13 is made in such a manner that when the fold is formed, it will rest between

said fold 13 and the marginal edge-portion 18 of the strip 10, as will be clearly understood from an inspection of Figures 4 and 5 of the drawings. To secure the completed fly or strip thus produced to the garment 19, the marginal edge-portion 20 of the latter is placed between the fold 14 and the marginal edge-portion 18 of the strip 10, the parts then being united by a row of stitching 21 passed through the assembled members, in the manner represented in Figures 2, 4 and 5 of the drawings.

In lieu of the manner of folding the main or base-strip 5 as shown in said Figures 1 to 7 inclusive, and as herein-above described, the said main or base-strip may be folded, as shown in Figure 8 of the drawings. In said Figure 8, the reference-character 22 indicates the main or base-strip, the same being longitudinally folded, as at 23 and 24, so as to provide the said strip upon its under or outer face with two folds 25 and 26, one of said folds as 26, being of greater width than the fold 25. The arrangement and manner of attaching the front or face-strip 90 to said main or base-strip 22, as well as the manner of folding the said front or face-strip, to cover the row of stitching 16 is the same as that hereinbefore described and illustrated in connection with Figures 1 to 7 inclusive of the drawings, and any further description of the same is therefore deemed unnecessary, such manner of attaching the said front or face-strip to said main or base-strip, and the folding of the same, being clearly shown in Figures 8 and 9 of the drawings.

Referring now to Figures 10, 11 and 12 of the drawings, there is shown in said drawings, a main or base-strip, as 27, the said strip being folded, as at 28, so as to provide an overlay member 29, which extends beyond the marginal edge-portion 30 of the main or base-strip 27, and is folded, as at 31, and turned under to provide the marginal lap 110 32. At suitable intervals, the said overlay member 29 is made with suitably formed openings or slits 33. Disposed in the spaces 34 formed between the said main or base-member 27 and the said overlay member 29, directly back of said openings or slits 33, are the main body-portions 35 of the garment-fasteners, as eyes, the hook-receiving portions 36 of said eyes being passed through said openings or slits 33, so as to rest upon the upper and exposed surface of the overlay member 29, substantially as illustrated in Figures 10 and 11 of the drawings. The front or face-strip in this construction is similar to that heretofore described in connection with Figures 1 to 9 inclusive, and the same consists of a main or body-member 37, which is longitudinally folded, as at 38 and 39, to provide two folds 40 and 41. The said body-member 37 is attached to the 130

said main or base-strip 27 by a line of stitching, as 42, which line of stitching, as well as the openings or slits 33 are covered and hidden from view by the fold 40, for the purposes of the present invention, and as will be clearly understood from an inspection of said Figures 10 and 11 of the drawings.

As shown, the line of stitching 42 in this case passes directly through the open parts 10 of the body-portion 35 of the respective eyes. The completed fly thus produced can then be secured to the garment 43, see Figure 11, by disposing the marginal edge-portion 44 of the latter between the fold 41 and the 15 marginal edge-portion of the strip 37, the parts then being united by the usual row of stitching which is passed through the assembled members.

Furthermore, it will be understood, that 20 any suitable forms of stitching may be employed with the fly-constructions hereinabove described.

It will be evident from the foregoing description of the present invention, that a 25 simple, neat, and well-appearing fly for garments has been produced, in which there are no lines of stitching exposed to view upon the face of the fly, except the line of stitching by means of which the fly is sewed fast 30 to the garment, and in which the maximum portions of the garment-fasteners used in connection with each fly are covered in such a manner, so that the danger of rusting and providing an unsightly garment is reduced 35 to a minimum.

I am also aware, that some changes may 40 be made in the general arrangements and combinations of the various devices and parts, without departing from the scope of the present invention as set forth in the foregoing specification, and as defined in the clauses of the claims which are appended to the same. Hence, I do not limit my present 45 invention to the exact arrangements and combinations of the several devices and parts as described in the said specification, and as illustrated in the accompanying drawings.

I claim:—

1. In a fastener provided fly for garments, 50 a base strip, a face strip disposed in parallel plane over said base strip, fasteners disposed between said base strip and face strip, a line of stitches joining said base strip and the main body of said face strip and traversing said fasteners, and said main body of said 55 face strip having a free forward marginal edge portion beyond said line of stitches adapted to fold backwardly over a garment

edge portion to conceal both the latter and said line of stitches.

2. A fastener provided fly for garments, comprising a base strip and a face strip with fasteners disposed therebetween, a line of stitches joining said base strip and face strip and traversing the fasteners to unite said elements in assembled relation, and said face strip having a free forward marginal edge portion beyond said line of stitches which is folded back upon the main body of said face strip to expose the operative ends of 70 said fasteners while at the same time concealing said line of stitches, said folded back portion also serving as a concealing binding for the raw edge of a garment inserted and secured beneath the same. 75

3. A fly for garments comprising a base-strip consisting of a main body-portion and folds folded under said body-portion, said body portion being provided with receiving slits, a face-strip upon said fold, garment- 80 fasteners having portions disposed between the body-portion and an underlying fold of the base-strip, said garment-fasteners having portions extending into and through said slits, a line of stitching sewed through 85 the body-portion and said underlying fold of said base-strip and through the body-portion of said face-strip, said face-strip having a portion folded over thereon, so as to hide the line of stitching and said slits from view. 90

4. A fly for garments comprising a base-strip consisting of a main body-portion and folds folded under said body-portion, said body portion being provided with receiving slits, a face-strip consisting of a body-portion, garment-fasteners having portions disposed between the body-portion and an underlying fold of the base-strip, said garment-fasteners having portions extending into and through said slits, the projecting portions of said garment-fasteners being disposed between the slit-provided portion of the base-strip and the body-portion of said face-strip, a line of stitching sewed through 100 the body-portion and said underlying fold 105 of said base-strip, through said fasteners, and through the body-portion of said face-strip, and a fold extending longitudinally from one of the marginal edge-portions of the body-portion of said face-strip and folded over thereon, so as to hide the line of stitching and said slits from view.

In testimony that I claim the invention set forth above I have hereunto set my hand this 10th day of May, 1922.

LEO ROSENMAN.
